UNITED STATES PATENT OFFICE.

LEVI E. SALISBURY, OF PROVIDENCE, RHODE ISLAND.

AUTOMATIC MULTIPLE-SHUTTLE TEXTILE-LOOM.

1,161,979.

Specification of Letters Patent. Patented Nov. 30, 1915.

Application filed October 16, 1913. Serial No. 795,492.

To all whom it may concern:

Be it known that I, LEVI E. SALISBURY, a citizen of the United States, residing at Providence, in the county of Providence and State of Rhode Island, have invented certain new and useful Improvements in Automatic Multiple-Shuttle Textile-Looms, of which the following is a specification.

The present invention relates to certain novel improvements in automatic looms for weaving textile fabrics, the loom being of the multiple-shuttle type in which continuously traveling non-reciprocating shuttles are employed. In fact, the improvements forming the subject of the invention here-with relate more particularly to the loom patented to me in the United States on the 10th day of February, 1903, No. 720,189, in which patent is shown a continuously traveling endless chain carrying spaced shuttles, each shuttle arranged to be successively charged singly and automatically with a length of mechanically selected weft-thread drawn, respectively, from relatively stationary spools or bobbins; the thus charged shuttles move in a progressive order and deliver the respective weft-threads successively between the suitably shedded sections of warp threads; each weft-thread or pick while being delivered by its shuttle between the pre-shedded sections of warp is successively beaten up into the fabric by the action of the immediately following respective sections of the comb or reed.

The objects sought to be attained by the present improvements are: to simplify and reduce the cost of the loom; to materially lessen its weight; to greatly reduce the area of floor space occupied by the loom; to successively and automatically temporarily reduce the speed of the propelled shuttles at the weft-charging station without varying the normal speed of the endless actuating or propelling chain; to provide improved means for beating-up the weft, and to produce a shuttle whose capacity for holding a given length of the infolded weft-thread is equal to a shuttle having a materially greater length, thereby permitting the loom to use a greater number of weaving units, thus increasing the output of fabric without increasing the length of the loom or its rate of speed.

In the seven accompanying sheets of drawings illustrating a multiple-shuttle loom embodying my present improvements, Figure 1

represents a front side elevation of the loom, substantially as in normal operation; Fig. 2 is a top plan view of it; Fig. 3 is an elevation showing the right end of the loom; Fig. 4 is a transverse section, in enlarged scale, taken on line 4-4 of Fig. 1; Fig. 5 is a plan view of a portion of the harness guides; Fig. 6 is a cross-section of one of the sections of heddle-frames of the harnesses, taken on line 6-6 of Fig. 4; Fig. 7 is a front elevation of the supported normally moving empty shuttle, in enlarged scale, at or near the shuttle-charging station, showing means for temporarily varying the shuttle's normal speed automatically; Fig. 8 is a similar view, showing the position of the shuttle at the end of its accelerated movement, immediately preceding the charging of the shuttle with a length of weft yarn; Fig. 9 is a corresponding top plan view; Fig. 10 is a side elevation of the shuttle itself; Fig. 11 is a top plan view, portions being broken away, showing the shuttle in the act of being charged; Fig. 12 is a transverse section, enlarged, taken substantially on line 12-12 of Fig. 11; Fig. 13 is a longitudinal central sectional view of a portion of the shuttle still further enlarged, showing a detail of construction; Fig. 14 is a plan view, showing the back end part of the shuttle, the top plate and portions of the shuttle-arms being omitted; and also representing the infolded weft thread being withdrawn from the moving shuttle; Fig. 14½ is a top plan view of the shuttle-arm represented in Fig. 12; Fig. 15 is a partial transverse sectional view of the frame, chain, etc., taken substantially on lines 15-15 of Figs. 1 and 8; Fig. 16 is a top plan view of a pair of the shuttle-propelling chain links, showing the cams for actuating the harness-controlling and weft-beating-up devices; Fig. 17 is a cross-sectional view, further enlarged, taken substantially on line 17-17 of Fig. 2, showing the individually movable dents of the beating-up comb; Fig. 18 is a sectional view, taken on line 18-18 of Fig. 17; Fig. 19 is a side elevation, also enlarged and in partial section, showing a portion of one of the harness plates, means for intermittently locking it to the arms of the harness actuator, and a pattern-chain adapted to be positioned or set so as to change the movements of the harnesses in "shedding" the warp yarns; Fig. 20 is a top plan view, in partial horizontal section, taken on line 20-20 of

Fig. 19; Fig. 21 is a vertical section, taken on line 21—21 of Fig. 19; Fig. 22 is a partial side elevation of a portion of the bar in which the intermediate or sub-indicators are movably mounted; Fig. 23 is a perspective view of one of the sub-indicators; Fig. 24 is a vertical section (corresponding somewhat with Fig. 4), taken substantially on line 24—24 of Fig. 19, and showing more clearly than in Fig. 4 a portion of one of the sections of harnesses, together with a pair of the actuator arms, the latter being represented in the fully closed, central position; and Fig. 25 represents the same arms and harness members when the arms are in the extreme divergent or open position. The relative positions of the cams or dogs d^3 , d^4 of the harnesses shown in Figs. 24 and 25 are indicated by dotted lines.

It may be stated that an automatic textile loom embodying the present improvements is capable of producing woven webs of cloth having identically the same appearance and general characteristics of similar goods woven on the usual reciprocating shuttle looms.

In the drawings the improved loom is represented as having a series of five weft-carrying shuttles continuously passing in a regular order or sequence between the shedded warp-threads, and having the weft-threads trailing from the respective shuttles successively beaten up into the web. As thus arranged, each temporarily working shuttle, together with its coöperating harness sections and beating-up means, may be termed a weaving unit. Obviously, the loom may be constructed and arranged so as to use a greater or less number of said weaving units. In my improved loom represented herewith five picks of weft-threads are successively continuously woven into the web, while the continuously traveling endless chain is moving a distance substantially equal to the width of the web.

The following is a detailed description of the more essential parts and instrumentalities or devices embodied in my improved automatic multiple-shuttle loom, including the manner of their operation. In view of the fact that the description of the several elements or devices are arranged under corresponding sub-titles, it is thought that a general description of the loom as a whole may be unnecessary.

Main frame of the loom.—The two spaced apart vertical end members a of the loom are connected together by the upper and lower horizontal chain-supporting and guiding ties a^1 , a^2 ; the front or breast beam a^3 ; a tie-bar a^4 supporting the rocking levers which operate the harness-actuator arms; and a pair of upper and lower tie-bars a^5 , a^6 to which the upper and lower harness-guides h^2 , h^3 are secured. To each of the outer ends

of the frame members a is fixed a semi-circular extension C^1 arranged in a vertical plane, the same constituting a continuation of the chain-track formed in said ties a^1 , a^2 , and also forming a supporting guide and path for the continuously traveling shuttles in their passage around the curved outer ends. The said members C^1 each encircle a sprocket-wheel B revolvably mounted in brackets a^8 secured to the respective frames a ; the said wheels being constructed to support the respective ends of the chain.

Driving mechanism.—The driving means, which may consist of any suitable or well-known arrangement, is represented as including in its construction a belt-driven loose pulley b^1 adapted to be clutched there-to by a member b^2 , which, through intermediate gearing, etc., rotates a shaft b to which is secured the chain-actuating sprocket-wheel B —see Figs. 1, 2, and 3. The loom is also provided with the usual warp-beam w^6 , take-up roll w^5 , and the winding cloth roll w^4 .

General arrangement of devices.—The drawings represent the loom as having the main driving mechanism located at the right and arranged to normally actuate the link-connected endless chain A in a continuous manner at a uniform rate of speed. The chain extends longitudinally along the front portion of the loom in a vertical plane; the upper and lower runs of the chain are substantially horizontal and parallel, the direction of movement of the upper run being from left to right. The chain is constructed and adapted to automatically actuate in the proper sequence practically all of the various devices or instrumentalities employed in the loom for controlling the production of woven textile fabrics. That is to say, the alternate links s of the chain are each caused to propel a guided shuttle carrying the weft-thread w^1 , and the intermediate links h control the movements of the several pairs of harness-actuator arms L , L^1 and the individually movable dents of the beating-up comb. The chain A is also employed for intermittently operating the devices for selecting the proper weft-thread and successively charging the shuttles with a length of the thread and for moving the prearranged pattern-chain X to position its members to engage the indicators of the vertically guided reciprocating harness sections H , whereby the latter are adapted to be positively locked to and unlocked from the said harness-actuator arms to cause the proper shedding of the warps. The reed proper, R , and also the adjacent shuttle-supporting guide C are removably seated in the stationary upper bar a^1 and maintained in position by clips a^{10} . See Fig. 4.

Main actuating chain.—The endless chain A consists of a plurality of connected uni-

formly spaced links s alternating with links h , mounted for continuous endwise movement in said frame ties a^1 , a^2 . Each pair of said links s , h , is provided on the upper 5 face with a strip h^5 having a wave-like cam-groove h^6 therein, the latter being continuous throughout the length of the chain. The grooved portion causes the individual dents of the comb K to successively beat up 10 the weft-threads into the web w^3 . The chain is provided on its underside with a continuous cam-groove h^7 adapted, in coöperation with levers l , l^2 , etc., to effect the shedding of the warp-threads carried by the several 15 harnesses. The cam parts proper of the said grooves are located in the links h , as stated, whereby the individual dents of the comb are successively moved into and out of normal action to beat up the portion of weft- 20 thread delivered from the immediately preceding shuttle and at the same time to properly position the corresponding sections of harnesses in advance of link s carrying the next succeeding weft-charged shuttle. The 25 straight portions of said grooves, h^6 , h^7 , formed in the links s act simply as guides to keep the beating-up and harness-actuating devices temporarily inactive until operated by the grooves of the following link h . 30 *Shuttle construction.*—My improved self-charging shuttles S are mounted on the several links s of the chain A, and slidably supported in the ways or track formed in said parts C, C'. Each shuttle is provided with 35 main upper and lower flat plates s^1 , s^2 having guide flanges s^3 on the back edge thereof; the upper plate s^1 has an open narrow longitudinal slot s^8 therethrough to freely receive the free ends c^2 of the weft-feeder arms c^1 , later described. To the rear end of 40 the shuttle is mounted a small revoluble wheel s^5 in normal frictional engagement with a wheel t^1 revolvably mounted in a bracket t fixed to the shuttle link s . The 45 shuttles are normally propelled through the medium of said elements s , t , t^1 and s^5 . To each of the outer longitudinal edges of the shuttle is pivoted at n^3 a straight row of uniformly spaced swinging light shuttle- 50 arms N; the pivots of one row alternating with those of the opposite row. The free ends of the arms N carry each a pair of spaced downwardly extending short pins n adapted to be temporarily engaged by the 55 weft; the base s^2 of the shuttle is provided with fixed upwardly extending spaced pins s^{10} alternating with one another on each side of the center line and arranged in relation to the said pins n of the respective arms 60 N. Fig. 11 represents the relative position of parts while the shuttle is being charged with the weft, and Fig. 14 shows portions of the shuttle while the weft is being drawn from its rear end. The latter figure more 65 clearly represents the weft as it is normally

engaged by and bent around the pins s^{10} and n . Fig. 11 also represents the opposed stationary cams s^9 , s^9 which actuate the shuttle-arms N of the traveling shuttles. In Fig. 14 n^1 indicates the median lines of the inwardly swung arms N; the upper plate s^1 and the major portions of four of the arms, however, (except the corresponding pins n) have been omitted in order to more clearly represent the appearance of the infolded or 70 threaded weft-thread. The full-line arrows in said Fig. 14 indicate the portion of the thread w^1 taken up by the last threaded arm r^1 during its arcuate movement of some 60° ; the dotted-line arrows indicate a similar 75 portion of the thread enfolded by the movement of the next arm r^2 and so on, alternately, in a regular order. Obviously, the two pins n of each arm coöperate with a pair of the relatively stationary alternately 80 arranged pins s^{10} in folding the thread. Practically each arm takes up (in moving from its normally open or empty condition to its normally charged condition) an amount of thread equal to four times its net 85 length, or four-fold. Each movable arm N of the shuttles is also provided with a device adapted to prevent it from moving too freely. See Fig. 13. The upper side of the 90 arm has a recess n^2 therein, located contiguous to the pivot-pin n^3 , in which recess is confined a very light spring n^4 , surmounted by a disk n^5 of felt, the latter pressing 95 yieldingly against the underside of the upper flat plate s^1 of the shuttle, the arrangement constituting a friction brake. 100

Device for temporarily varying the speed of shuttle.—At or near the shuttle-charging point or station, at the upper left end of the loom, the chain-supporting frame C' is provided with a bracket T¹ having its upper portion extending inwardly over the chain; to the bracket is secured a longitudinal plate T positioned edgewise in a vertical plane and provided with an elongated cam-groove t^7 . The said bracket or stand t , carrying the wheel t^1 , is provided on its back face with an angularly movable, normally seated arm t^2 having its upper free end adapted, when in use, to engage the rear end of the shuttle 110 and temporarily force the latter ahead a short distance at an accelerated rate of speed, say double that of the normally moving chain. See Figs. 1, 7, 8, 9, and 15. The lower end of the arm t^2 is secured to the rear end of a shaft t^8 movably mounted in the lower part of bracket t , while a small toothed spur gear t^9 is fixed to its opposite end, said gear being in continuous mesh with a similar gear t^{10} adapted to turn on a 115 stud fixed in said member t . A flat link or arm t^5 is secured to the front face of the last-named gear; and having the free end of said arm t^5 provided with a pin t^6 normally positioned to enter the open cam- 120

groove t^7 of said plate T; the groove being so arranged that when the pin t^6 of the normally propelled shuttle enters the groove (See Fig. 7) the continued normal travel 5 of the bracket t will guide the pin downward in said groove, thereby moving the gears in the arrow-direction and causing the free end of arm t^2 to engage the shuttle and temporarily propel it ahead at double 10 the normal speed preparatory to charging the shuttle; the position and relation of the parts then being substantially as shown in Figs. 8 and 9. The continued normal advance of the chain causes the pin t^6 to move 15 upwardly in the cam-groove while the shuttle-charging operation is being effected; the rate of speed, however, of the advancing shuttle, in connection with the temporarily reduced movement of the upper engaging 20 end of the arm t^2 , meanwhile being but one-half that of the speed of the chain, the result being to practically double the length of time in which to charge the shuttle. The 25 normal relation of the several parts will be resumed substantially at the instant the pin t^6 passes from the forward end z of the cam; the action just described being successively repeated during the charging of each shuttle.

30 *Weft-selecting and feeding means.*—E indicates generally the mechanism employed for said purposes, the same comprising suitably driven sprocket-wheels x^3 carrying the usual pattern-chain provided with series of sinkers x^5 and risers x^4 arranged to engage and actuate pivotally mounted levers c jointed to bars c^1 endwise movable horizontally in the head of a fixed bracket c^3 —see Fig. 15, &c. The inner ends of the members c^1 are each provided with an eye c^2 through which the weft-thread w^1 passes from the respective spools w^2 . The said eyes c^2 are adapted each to carry a different thread and to be automatically positioned singly in 40 the path of the channel s^8 of the respective shuttles and somewhat in advance of the latter, in accordance with the prearranged order of the threads. The feeders, assisted by springs c^4 , are retracted to the normal position 45 immediately after the shuttle has passed.

50 *Weft beating-up device.*—This device K is shown most clearly in Figs. 17—18. To the back of the horizontal plate a^9 , fixed to the front of the said tie-bar a^1 , is secured a member k^8 extending longitudinally across the loom and provided with spaced thin ears k^4 , in which ears a rod k is supported. A series of individual dents k^1 , alternating 55 with said ears, forming a comb, are movably mounted on the rod and having the lower portion k^2 of each dent in engagement with the groove k^6 of the continuous cam-plates k^5 secured to the upper face of chain A. The arrangement being such that the

dents are swung successively into and out of action between the warps w immediately preceding and following the passage of the respective shuttles. The upper free ends of the dents are preferably made wedge-shaped, as indicated at k^6 , Fig. 18.

Harness actuating and controlling means.—The drawings represent twenty-four laterally spaced independent heddle-carrying harnesses H, divided longitudinally into fourteen sections H^1 , each harness portion fixed to a thin blade h^1 mounted to reciprocate in spaced slots h^4 formed in the stationary upper and lower horizontal guide plates h^2 , h^3 . See Figs. 1 and 4. As hereinbefore stated, the harnesses of each section or group are reciprocated vertically by means of a pair of connected rock-levers l , l^2 , pivoted to the horizontal tie or bar a^4 . The upper end of lever l is in continuous operative engagement with the cam-groove h^7 formed in the lower face of the links of chain A; the lever l^2 being jointed at its lower end to a strap-link i^2 , in turn jointed to upper and lower links i , i^1 , fulcrumed respectively to the heads j , j^1 , to which are secured the respective horizontally extending upper and lower harness-actuator arms L, L^1 . The said members j , j^1 are fulcrumed at j^2 to a partition of the casting a^2 . As thus 95 constructed, the movements of the rock levers l , l^2 , are caused to positively open and close the arms L, L^1 through the medium of what may be termed a toggle-jointed connection.

Indicators, etc.—The means employed for positively and progressively indicating and effecting the action of the harness sections are substantially as follows: The pre-arranged step-by-step moving harness-pattern-chain X, having, say a series of twenty-four sections—one section for each harness—is disposed transversely of the loom, the sections being provided with the well-known risers and sinkers x^1 , x^2 , arranged or assembled to produce the "weave" desired. The several harnesses, twenty-four being represented, are divided longitudinally of the loom into fourteen sections or groups, each group being actuated by a pair of the said arms L, L^1 , whose opening and closing movements are controlled by the said cam-groove h^7 of the main chain A, operating through said intermediate connections. Figs. 19 to 25, inclusive, show the construction and arrangement of means for automatically detachably connecting said arms to a section of harness. Fig. 19 represents a member of the initial section of harness having its blade h^1 carrying the front indicator d^1 engaged by a pre-arranged riser-roll x^1 of the pattern-chain X; the indicator is horizontally slideable and having its opposite end d^2 engaging the lower part of a small rock-arm e centrally 100

105

110

115

120

125

130

pivoted to the blade; the latter has an upper arc-shaped opening therein through which a lug e^2 of the rock-arm extends, the lug being engaged by the rear end d^2 (see 5 dotted lines) of the back indicator. The upper and lower end portions e^1 of the arm e are engageable, respectively, with lugs f^2 of hooks f , f^1 pivoted to the blade h^1 ; the latter being provided with independent vertically 10 arranged upper and lower alining narrow central slotted openings h^8 , h^9 , through which the said arms L , L^1 extend. The proximate edges of the arms bear against the central ties h^{10} separating the 15 slots h^8 , h^9 . In Fig. 19 the arms are indicated sectionally in the closed position, all the harnesses of that section then being level in the mid-position. As thus constructed and arranged, the indicators 20 mounted on the front side of the blades h^1 of the several sections of the harnesses are caused to lock the upper hooks f to the upper edge of the arm L and the indicators on the opposite side of the blades operate 25 in a similar way to actuate the lower hooks f^1 to lock the latter to the lower edge of the arm L^1 . The drawings represent the movable indicators d^1 located on the central line Q ; this line designates the neutral or level 30 mid-position of the harnesses. See q , Fig. 1. At the right edge of and projecting from the blades are fixed vertically spaced upper and lower dogs or cams d^3 , d^4 , disposed with respect to the line Q , cam d^4 being on the 35 front side below the center line and cam d^3 being above the line and on the opposite side of the blade. As thus constructed and arranged, the short lengths of the several harnesses of the next advance section or 40 group are caused to be engaged and positioned by the centrally located sub-indicators d slidably mounted in the corresponding transverse bar D fixed to members d^5 secured to the frame ties a^5 . That is to say, the blade when locked to the upper arm L positions the lower dog d^4 on the line Q when it (the arm) is in the extreme upper 45 position. Conversely, the movements of the lower fellow arm member L^1 , when locked to the blade, positions the upper dog d^3 on the line Q when the last-named arm is in the extreme lower end of its stroke. See also Figs. 24-25. Obviously, when the upper arm is locked to the blade of the harness, 50 the lower arm is in the unlocked condition, and vice versa. Thus, it is evident that the front indicators d^1 of the movable vertically guided harness-blades h^1 , in coöperation with said members d , e , e^1 and f^2 , operate to swing the upper latches or hooks f and lock them to the upper arm L , the lower arm L^1 then being unlocked from its hooks f^1 . The indicators on the back of the blades operate in a similar manner to lock 55 the hooks f^1 to the lower arm L^1 , arm L then being unhooked; the action taking place when the arms are fully closed relatively to the mid-position or center line Q . The operations above described successively follow one another in a progressive order 60 lengthwise of the harnesses, from left to right. Figs. 24 and 25 indicate in enlarged scale, the same pair of arms in the closed and open positions, respectively, and also showing alternate harnesses hooked to the 65 upper arm L , and the intermediate harnesses locked to the lower arm L^1 . The dogs d^3 , d^4 , upon arriving at the center line Q , according as the harness is moving down or up, are caused to engage the respective sub-indicators d , thereby moving the latter endwise to set or position them in advance, so as to be engaged by the corresponding indicators d^1 of the next succeeding harness 70 section. 75

Means for actuating the weft-selecting and harness-changing devices E , X . (See Figs. 1, 2, and 15.)—To the upper left end of the loom is slidably mounted a transverse bar p having its rear end in continuous engagement with the said cam-groove h^7 of the traveling chain A ; the front end of the member p being adapted to engage the teeth of a ratchet-wheel p^1 fixed to a suitably mounted shaft p^3 (Fig. 15), to which 80 sprocket-wheels x^3 carrying the pattern-chain of the said weft-selecting device E are secured. A pair of angle gears p^4 , actuated by the movements of shaft p^3 , together with intermediate mechanism, are caused to 85 actuate the harness pattern-chain X in a step-by-step manner. See also Fig. 1. I make no claim, however, to means for effecting the movements of the weft-selecting and harness-changing devices. 90

Weft stop-motion device.—At the right end of the loom is pivoted a normally stationary short vertical stop lever b^5 having its lower end disposed immediately over the shuttles; the said lever, when brought into 95 action, is adapted to trip a suitably mounted rod b^4 connected in turn to a clutch member, as b^2 . An arc-shaped slot s^7 is formed in the upper plate s^1 of each shuttle near the pilot end s^4 , through which slot extends 100 a pin s^6 fixed to the foremost swinging shuttle-arm N . See Figs. 9 and 11. In the normal operation of the shuttles the latter successively emerge empty from the warps, thus 105 indicating that the weft has been properly delivered from the shuttles during their transit across the loom, the several arms N then being open, corresponding with the unfolded position, thereby, too, swinging the pin s^6 of the forward arm rearwardly in its 110 slot so as to escape the said stop lever. If, however, the shuttle has failed to deliver all or a portion of its pick, or even not to have been charged at all, the said pin s^6 of the forward infolded arm will engage and actu- 115 120 125 130

ate the stop-lever to release the clutch and stop the loom. The loom is adapted to be started and stopped through the medium of a manually operable lever b^3 , also connected 5 to rod b^4 .

Means for actuating the take-up roll.—The cloth take-up roll, w^5 , indicated in Figs. 1, 2, and 3, is adapted to be actuated in an intermittent manner by means located at 10 the upper right end of the loom. Said means consisting of a horizontal, slidably mounted transverse bar u having its rear end adapted to engage and be actuated by the cam groove h^7 of the moving chain A ; the front end of 15 the bar has a pawl engaging a ratchet-wheel u^1 fixed to a vertical shaft u^2 , the latter having a worm u^3 at its lower end engaging a wheel u^4 secured to the shaft or trunnions of the take-up cloth roll in a well-known 20 way. The upper end of shaft u^2 is arranged to receive a handle, thereby adapting the device to be manually actuated when desired.

I claim as my invention:—

25. 1. In a textile loom having a stationary reed, an endless flexible driving element capable of continuous movement in one direction, a plurality of spaced independent shuttles arranged to be propelled by said driving element, means for automatically successively charging the shuttles with weft-thread, means for shedding the warps in sections for the passage therebetween of said charged shuttles while the latter are delivering the weft therefrom, a comb extending longitudinally of the loom, said comb comprising a plurality of independently movable dent members mounted on a stationary support, and means actuated by said 30 flexible driving element to cause the dents to oscillate on said support in a regular order or sequence and beat up into the fabric the weft delivered from the respective shuttles.
40. 2. In a textile loom of the general character described having a stationary reed, a propelled main actuating endless chain or element, and a plurality of intermittently actuated harnesses divided into sections for carrying the warps, the combination therewith of a plurality of supported independent shuttles arranged to be propelled by said chain, means for automatically charging the moving shuttles singly with a length of weft thread, and a comb having individually movable weft-beating-up dents actuated by said chain and mounted on a stationary support, said comb being located longitudinally of the loom and in front of the shuttles, and 45 having the free ends of the dents arranged to extend upward through the warps.
45. 3. In a textile loom of the general character described provided with a stationary reed and means for weaving into the warp successive lengths of weft-thread delivered

from propelled automatically charged independent shuttles arranged for continuous movement in one direction, the combination therewith of a comb having individually movable dents, adapted to successively engage the weft and beat the same into the web, means consisting of a suitably supported and driven endless chain having joint connected links for propelling said shuttles, and means carried by the chain for actuating the dent members of the comb, for the purpose set forth.

4. In a multiple-shuttle loom of the character described, the combination with means for intermittently charging shuttles with weft-thread, of an endless driving chain continuously movable at a normal rate of speed, shuttles actuated by the chain, and a device for automatically increasing the shuttle's speed before said shuttle is charged with the weft and also arranged to temporarily retard the shuttle's movement below the normal speed of the chain during the weft-charging operation.

5. In a non-reciprocating multiple-shuttle textile loom of the general character described provided with an endless actuator chain arranged for continuous movement at a normal rate of speed, a plurality of spaced, supported and guided empty shuttles propelled by the chain and means for automatically varying the speed of the shuttles singly immediately preceding and during the charging of the shuttles with the weft-thread, without varying the normal speed of the chain.

6. In a non-reciprocating multiple-shuttle textile loom of the general character described, an endless chain, means for moving the chain at a normal rate of speed, independently mounted shuttles propelled by said chain, a weft-charging station, means carried by the chain, in cooperation with a stationary element located contiguous to the weft-charging station, for automatically accelerating and retarding the shuttle's normal movement, for the purpose set forth.

7. In a non-reciprocating multiple-shuttle textile loom of the general character described, the combination with an endless chain, means for actuating the chain, and a plurality of supported chain-propelled shuttles, a plurality of harnesses divided into sections, means controlled by said chain for actuating the harness sections, and means, controlled by an intermittently movable pattern-chain for detachably locking the members of the harness sections to the actuators.

8. In a multiple-shuttle textile loom, a plurality of warp harnesses, each harness being divided into sections, a pair of opposed actuator arms engaging the respective harness portions of the corresponding section, a suitably supported endless chain-like traveling element provided with a plurality of

links jointed together, means coöperating with said links and with the corresponding pair of actuator-arms for moving the latter toward and from each other, and means, including endwise movable indicators, positioned by a pattern-chain, for locking the said harness portions of a section to the actuator-arms and for releasing them therefrom.

9. In a multiple-shuttle textile loom having an endless chain, and means for moving the latter at a normal rate of speed, a plurality of warp harnesses divided into sections, pivoted upper and lower actuator arms disposed in a vertical plane, adapted to engage the several harnesses of the corresponding section, means, including a toggle-jointed connection actuated and controlled by said chain, for operating said arms, and controlled means for automatically locking the actuator arms to said section of harnesses and for unlocking them therefrom.

10. In a textile loom of the non-recipro-cating-shuttle type, provided with an endless driving member, and means for moving

said member at a normal rate of speed, the combination therewith of a shuttle propelled by the driving member, means for selecting a weft-yarn for the shuttle and automatically charging the latter, while it is in motion, with a predetermined length of said selected weft-yarn, means acting to gradually accelerate the speed of the normally moving shuttle in advance of the weft-charging operation, and means for retarding or slowing-down the normal speed of the shuttle while the latter is being charged with the weft, whereby the guided empty shuttle is caused to temporarily travel for the instant faster than the normally moving endless driving member, so as to provide a relatively longer interval to be utilized in the actual weft-charging process.

11. In testimony whereof I have affixed my signature in presence of two witnesses.

LEVI E. SALISBURY.

Witnesses:

GEO. H. REMINGTON,
CALVIN H. BROWN.
